FIREARM

Val A. Browning, Ogden, Utah, assignor to J. M. &
M. S. Browning Company, Ogden, Utah, a cor-
poration of Utah

Application February 8, 1938, Serial No. 189,293
In Belgium June 29, 1937

16 Claims.

(Cl. 42—42)

This invention relates to improvements in firearms and more particularly to firing mechanism for double barrel guns (either of the side-by-side or the over-and-under types) in which the barrels may be fired in succession upon successive intentional pulls of a single trigger.

In firearms of the double barrel, single trigger type, various arrangements of sear trips or connectors are used, and means are provided for selectively setting the trip or connector to fire one barrel and then the other. In the manufacture of this type of gun, the ideal condition is to have the sear rest directly on the sear trip.

However, in manufacturing, and particularly in production manufacturing, it is almost impossible to prevent some slight clearance between the sear trips and the sears, and, likewise, it is extremely difficult to have the sears in perfect transverse alignment. Because of these difficulties, in providing a connector which is laterally shiftable from under one sear to under the other, it is generally necessary to enlarge the clearance between the sears and sear trips to prevent any catching of the trips on one sear which may be slightly lower than the other. Where a pivotal sear trip is used, the clearance between same may become so large as to produce a noticeable lost motion in the pulling of the trigger.

It is an object of this invention to overcome these and other disadvantages heretofore found in this type of gun.

A further object is the provision of a connector or sear trip which, in being shifted to selectively engage one or the other of the sears, is always drawn longitudinally out of relative position to the sears, then transversely shifted relative thereto, and then longitudinally returned into position relative to the sears.

A further object of the present invention is an improved selector means for adjusting the sear trip or connector to initially fire either one or the other of the barrels; the selection being accomplished by a compound movement of the selector means.

A still further object is a connector which is universally mounted and having operative connections with the selector means whereby it will follow the compound movement thereof into the selected position.

A still further object is a selector which may be located remotely from the trigger and which will give immediate visual indication as to the setting thereof and when once set cannot be accidentally shifted from one position to another.

A still further object is a trip or connector which is universally mounted on and pivoted to the trigger and movable laterally and longitudinally relative thereto.

A still further object is an improved means for mounting the sear trip or connector on the trigger and for mounting the selector means on the frame with positive operative connections to the connector.

A further aim of the invention is to provide a firing mechanism having the above and other advantages, which is characterized by its simplicity in construction, its use of a minimum number of parts, its ease of assembly, economy in manufacture, its durability, and by its reliability and effectiveness in operation.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a side view partly in section showing an embodiment of the invention with the sear trip or connector held in safety position by the selector means;

Fig. 2 is a view similar to Fig. 1 but showing the connector selectively positioned behind the left-hand sear;

Fig. 3 is a view on line 3—3 of Fig. 2;

Fig. 4 is a view on line 4—4 of Fig. 2;

Fig. 5 is a detail view of the connector-trigger mounting;

Fig. 6 is an exploded perspective of the selector means and connector-trigger mounting; and

Figs. 7 to 9 are diagrammatic views illustrating the compound movement for selectively positioning the connector.

Referring to the drawings, 10 designates the frame of the gun; only a part thereof being shown as it may be of any suitable construction. The firing mechanism comprises a pair of hammers pivoted as at 14 and provided with sear-receiving seats or notches 15. Respectively associated with the hammers is a sear 16; the shape and positioning of same depending upon the type of hammers used. In the embodiment shown, the sears are pivoted at 20 to the upper tang piece 22. Each sear is provided with a hammer-cooperating tooth 24 adapted to be seated in a cooperating hammer notch 15, and a

rearwardly extending tail piece 25 adapted to cooperate with a sear trip or connector.

The hammers are normally urged into firing position by a main spring 27 encircling a guide 5 plunger 29, one end of which engages the hammer and the other end being slidably mounted in an opening 30 in the rear tang piece 32 of the frame. Thus, when the gun is cocked, the sear tooth 24 of each sear engages in notch 15 of its respective hammer and plunger 29 is simultaneously moved rearwardly, compressing spring 27 to constantly urge the hammer toward fired position.

Associated with the sears is a sear trip or connector 35, having, adjacent its upper end, a forwardly extending sear-engaging lug 38 provided with an upwardly facing shoulder 40 and, on its respective side surfaces, lugs 42 and 44 having upwardly facing shoulders or surfaces 20 43 and 45 generally in the plane and spaced rearwardly of shoulder 40. The shoulder 40 is of less width than the spacing between the sear tails 25 (see Fig. 3), thus preventing simultaneous engagement of both sears by the connector shoulder; whereas the connector above the shoulder 40 is wider than the opening between the sear tails to prevent same from entering therebetween.

The connector is mounted at its lower end 30 on a trigger 46 pivotally mounted on the lower tang piece 47 of the frame. Mounted on the upper end of the connector is an inertia block 49 which is provided with a forwardly projecting lug 50 having a vertical opening 52 there-through and a pair of forwardly projecting positioning wings 54 spaced below same. The block is mounted loosely on a reduced part 56 of the connector which is received in opening 52, the wings 54 straddling the connector beneath the 25 lugs 42 and 44 to position same thereon; there also being provided a spring 55 which fits into a small bore in the block and abuts against the rear face of the connector to constantly urge the block rearwardly therefrom.

45 The particular arrangement of sears, hammers, connector, and inertia block as heretofore described may be used; the particular advantages and detailed description thereof being set forth in my co-pending application Serial 50 No. 87,153, now Patent No. 2,203,378, filed June 25, 1936.

In accordance with the present invention, the connector 35 is universally mounted on the trigger 46 and is capable of longitudinal and lateral 55 swinging movement relative thereto. As may be seen from Figs. 3 to 5, the lower end 55 of connector 35 is pivotally mounted on a pin 57 carried by the bifurcated end 59 of a connector carrying pin 58. The pin 58 is of circular cross 60 section and adapted to loosely fit in a bore 60 in trigger 46, the pin having a reduced forwardly extending part 61 and a forwardly facing shoulder 62. Intermediate of shoulder 62 and the rearwardly facing end wall 63 of the 65 pin-receiving bore is a spring 64 which normally urges pin 60 outwardly in the bore and performs other functions hereinafter set forth. A segment of the bore is cut away to leave a longitudinally extending slot 66 of greater width 70 than the connector, thereby allowing the connector to be pivoted laterally and longitudinally relative to the trigger. The trigger is further provided with upwardly extending, spaced apart wall members 68 in which is fixed a stop pin 79 75 against which the connector 35 is normally urged.

The stop pin 79 prevents the connector carrying pin 58 from being forced outward from bore 60 by spring 64 and, being located above the trigger pivot 48, the force resultant therefrom acts to maintain the trigger in its lowermost 5 position.

The positioning of the connector is controlled by a longitudinally and laterally movable safety latch 71 which is located on the top tang piece 22 of the frame. The latch 71 is provided with two depending fingers 72 and 74; the finger 72 operatively connecting or engaging the inertia block 49 to move same and control the positioning of the connector. The fingers extend into a guideway 76 in the top tang piece; the guideway being generally the shape of a distorted U having a rectangular opening 79 and oppositely disposed parallel slots 80 and 81 extending forwardly therefrom to either side of a rearwardly extending tongue 78; the slots 80 and 81 to either side thereof being approximately the width of the inertia block engaging finger 72, and the length of the rectangular opening is approximately the over-all length between the front and rear edge, respectively, of the depending fingers. Intermediate of the fingers 72 and 74 is a positioning block 82 of equal width to guideway 76 and of a length approximately equal to the distance between the fingers. The safety latch 71 and block 82 are held in place by the usual spring member 84 which is provided with a slot 85 and a detent 86. The slot 85 receives the inertia block engaging finger 72 when the slide is placed at right angles thereto and the spring locks in the cut-away portions 73 at 35 the lower end of the finger 72 when the slide is returned to its normal position. When so secured, the spring detent 86 may be received in one of the detent notches 87 or 89 in the lower face of the upper tang piece, and, in addition 40 to securing slide 71, the spring also serves to position and hold block 82.

The inertia block engaging finger 72 extends through and below the guideway 76 and is receivable in a slot 90 in the top of the inertia block 49, which slot terminates short of the rear end of the block in a forwardly facing shoulder 91. The width of slot 90 in the top face of the block is approximately that of the finger and then widens out in the body of the block. In the embodiment illustrated, there is provided a circular hole 92 beneath the slot 90 and extending from the rear face of the block inwardly; this construction permitting of easy manufacture as it may be readily drilled therein; the edge of the slot in the top of the block serving as a fulcrum about which the block 49 may pivot relative to finger 72.

In operation, it may be assumed that the gun is set as shown in Fig. 2 and as diagrammatically 60 illustrated in Fig. 7; the free end of the connector 35 is tilted towards the left side of the gun (as seen from the stock), with the connector shoulder 43 located beneath the tail 25 of the left sear 16. In like manner, safety slide 71 is displaced laterally to the left side of the frame, giving immediate visual indication that the left sear is to be initially tripped. As may be seen in Fig. 7, the inertia block engaging finger 72 is located in slot 80 of guideway 76 and the guideway 70 tongue 78 prevents lateral displacement of the safety latch 71. It will also be seen that binding of finger 72 and inertia block 49 is prevented because of the enlarged opening 92 beneath the surface slot 90; it being apparent that if the 75

slot were not widened out, the finger 72, which always remains vertical, would bind against the side wall thereof. In this position, trigger spring 64 serves the further function of urging the pivoted end of the connector rearwardly, and as the connector abuts against pin 70 at a point above the trigger pivot 48, spring 64 further acts to urge the trigger downwardly.

If it is desired to change the setting and place the connector in selected relation to the right-hand sear, it is necessary to do so through a compound movement of the safety slide 11. The slide must first be moved longitudinally and rearwardly until finger 72 clears tongue 78 (Fig. 8). The movement of the safety slide also carries positioning block 82 rearwardly with it, and inasmuch as finger 72 will abut against the shoulder 91 of the inertia block, the inertia block will likewise be moved rearwardly, pivoting connector 35 about pin 57 and moving the connector out of operative relation to the sear. This movement likewise causes detent 86 of spring 84 to be released from its cooperating notch 87 in the upper tang piece of the frame and engage notch 25 in the safety position. The safety slide may now be moved laterally to the right-hand side of the gun to the dotted line position indicated (Fig. 8), and because of the close fit of the positioning block 82 between fingers 72 and 74, no twisting 30 movement of the slide 11 may occur during the lateral movement thereof. As the safety slide 11 is moved laterally, the inertia block engaging finger 72 will also cause the inertia block to move laterally simultaneously therewith, and inasmuch 35 as the connector and block are pivoted for lateral swinging movement, whereas the finger 72 remains vertical, the block will fulcrum about the edge of the slot 90 in the upper face thereof to its new angular position behind the right-hand sear. The slide 11 may now be moved from the dotted line forwardly to the position indicated in Fig. 9, whereupon the shoulder 40 of the connector will be beneath the right-hand sear of the gun. In this position, detent 86 will again enter the cooperating notch 87 and hold the latch in position. It is apparent that when 45 the inertia block engaging finger is rearwardly of the tongue 78 the connector will also be out of operative position and the gun cannot be fired, and, when so positioned, the detent 86 is brought into engagement with the rear cooperating notch 89, whereupon the parts will assume the position shown in Fig. 1.

In firing, the action is generally similar to that described in the aforementioned application, Serial No. 87,153. Assuming the left barrel is to be initially fired, trigger 46 is pulled, raising connector 35 and left sear 16. Trigger 50 spring 64 will tend to hold the connector against the sear and prevent the connector from moving under the right sear during recoil. However, as the gun rebounds, the inertia block will cause the connector to lag, permitting the left sear to fall, and when the connector moves forwardly, the right-hand side lug 45 thereof will be positioned under the right-hand sear 16, whereupon the second barrel may be fired.

As many changes could be made in the above 70 construction and many apparently widely different embodiments of this invention could be made without departing from the scope thereof, it is intended that all matter contained in the above 75 description or shown in the accompanying draw-

ings shall be interpreted as illustrative and not in a limiting sense.

It is also to be understood that the language used in the following claims is intended to cover all of the generic and specific features of the 5 invention herein described and all statements of the scope of the invention which, as a matter of language, might be said to fall therebetween.

I claim as my invention:

1. In combination, a frame, hammers, sears 10 respectively associated therewith, a trigger, a connector carried by said trigger and transversely movable relative thereto to lie positioned relative to one of the sears, a transversely and longitudinally movable member mounted on the 15 frame, and operative connections between said member and connector whereby said connector may be selectively engaged with either sear.

2. In combination, a frame, hammers, sears 20 respectively associated therewith, a trigger, a connector pivoted on said trigger and transversely movable thereto to be positioned relative to either of the sears, a transversely and longitudinally movable member mounted on the 25 frame, and operative connections between said member and connector whereby said connector may be selectively engaged with either sear.

3. In combination, a frame, hammers, sears 30 respectively associated therewith, a trigger, a connector pivoted on said trigger and transversely movable thereto to be positioned relative to either of the sears, a longitudinally and transversely movable member on the frame, and operative connections between said member and connector whereby movement of said member 35 will move said connector to the selected position.

4. In combination, a frame, hammers, sears 40 respectively associated therewith, a trigger, a connector mounted on said trigger and movable transversely thereto, an inertia block carried by 45 the connector, a movable member on the frame, operative connections between said member and said inertia block whereby movement of said member will move said block and connector to the selected position.

5. In combination, a frame, hammers, sears 50 respectively associated therewith, a trigger, a connector having one end pivoted on said trigger and transversely movable thereto to position said relative to either of the sears, an inertia block carried by the connector, a slidible member on the frame, and operative connections between said member and said inertia block whereby movement of said member will move said block and connector to the selected position. 55

6. In combination, a frame, hammers, sears 60 respectively associated therewith, a trigger, a connector adapted to be associated with either of the sears, a universal joint between one end of the connector and the trigger, an inertia block carried on the other end of the connector, a slidible member carried on the frame, and an operative connection between said member and said inertia block whereby movement of said 65 member will move said block and said connector to the selected position.

7. In combination, a frame, hammers, sears 70 respectively associated therewith, a trigger, a connector mounted on the trigger and adapted to be selectively positioned relative to either of the sears, a movable member on the frame for selectively moving the connector to the selected position, said frame having a guideway extending transversely and longitudinally of the frame, 75

and means connecting said member and said connector and laterally and longitudinally movable in said guideway.

8. In combination, a frame, hammers, sears

5. respectively associated therewith, a trigger, a connector universally mounted on the trigger to be selectively positioned relative to either of the sears, a movable member on the frame, said frame having a transversely and longitudinally 10 extending guideway, means connecting said member and said connector and transversely and longitudinally movable in said guideway, whereby movement of the member will move said connector to its selected position.

15. 9. In combination, a frame, hammers, sears respectively associated therewith, a trigger, a connector having one end universally mounted on the trigger, an inertia block carried on the other end, a movable member carried on the

20 frame, a finger depending from said member and engaging said inertia block, said frame having a transversely and longitudinally extending guideway through which said finger extends, whereby movement of said finger in said guideway by said member will simultaneously move said block and connector.

30 10. In combination, a frame, hammers, sears respectively associated therewith, a trigger, a connector having one end universally mounted on the trigger and adapted to be selectively positioned relative to the sears, an inertia block carried by the other end of the connector, said block having a longitudinally extending opening in the upper surface thereof, a movable member 35 on the frame, a finger depending from said member and extending into the opening in said inertia block, said frame having a transversely and longitudinally extending guideway through which said finger passes, whereby movement of said finger in said guideway by said member will simultaneously move said block and connector.

40 11. In combination, a firearm, hammers, sears respectively associated therewith, a trigger, a connector adapted to be positioned relative to the sears, a safety slide mounted on the top face of the frame, a pair of fingers depending downwardly from said slide, a block receivable between said fingers, a guideway in the top face of said frame, said guideway having a rectangular opening approximately the width of the block and of a length equal to the over-all length between the forward and rear edge of said fingers and having a pair of oppositely disposed slots 50 extending forwardly from the rectangular opening, said slots having approximately the width of the forward finger on said safety slide, a spring, means for securing the spring to said forward finger for maintaining said slide and block in position, and operative connections between said finger and connector whereby move-

ment of said slide in the guideway will move said connector.

5. 12. In combination, a frame having sears respectively associated therewith, a trigger, a connector mounted on the trigger and adapted to be moved transversely relative thereto, an inertia block mounted on said connector, said block having a slot adjacent the top thereof, the face of said slot being relatively narrow at the surface of the block and widening out beneath the surface of the block, a slidable member carried on said frame and mounted for transverse movement thereof, a finger depending from said member and extending into the slot in said inertia block, the opposed edges of said slot being fulcrum points whereby when said member is moved transversely of the frame said block may pivot about said finger.

10. 13. In a firearm of the character described, a trigger having a longitudinal circular bore 20 therein, a circular pin mounted in said bore, a spring intermediate of the pin and the end wall of the bore, a connector mounted on the pin, and a transversely extending stop pin carried by said trigger and positioned above said 25 bore and rearwardly of the connector.

15. 14. In a firearm of the character described, a trigger having a longitudinally extending circular bore therein, a circular pin mounted in said bore, said pin terminating in a bifurcated 30 end, a connector pivotally mounted in the bifurcated end of the pin, a spring intermediate of the other end of the pin and the end face of the bore, and a transversely extending stop pin carried by said trigger and positioned above 35 said bore and rearwardly of the connector.

20. 15. In a firearm of the character described, a frame, a trigger pivoted to said frame, said trigger having a longitudinal circular bore therein, a circular pin carried in said bore, a 40 spring intermediate of one end of the pin and the end face of the bore, a connector pivotally mounted on the other end of the pin, and a transversely extending stop pin carried by said trigger and positioned above the pivotal point 45 of the trigger and rearwardly of the connector, whereby said spring will urge the connector into abutment with said transverse pin and maintain the trigger in its lowermost position.

25. 16. In a firearm of the character described, a frame, a safety latch having a pair of downwardly depending fingers, a block adapted to be positioned between said fingers, said block being substantially wider than said fingers, a guideway in said firearm having generally the shape 50 of a distorted U, one of said fingers extending through the guideway and beneath said frame, and a spring inside said frame and adapted to be interlocked with said finger to maintain said safety latch in position.

60 VAL A. BROWNING.
